J. H. HESLAR

AUTOMATIC CUT-OFF VALVE

Filed Feb. 21, 1922

Inventor

J. H. Heslar

By William C. Linton.

Attorney

UNITED STATES PATENT OFFICE.

JAMES H. HESLAR, OF MUSKOGEE, OKLAHOMA.

AUTOMATIC CUT-OFF VALVE.

Application filed February 21, 1922. Serial No. 538,232.

To all whom it may concern:

Be it known that I, JAMES H. HESLAR, a citizen of the United States of America, residing at Muskogee, in the county of Muskogee and State of Oklahoma, have invented certain new and useful Improvements in Automatic Cut-Off Valves; and I do hereby declare that the following is a full, clear, concise, and exact description of the invention, such as will enable others skilled in the art to which it appertains to make and use the same.

This invention relates to improvements in safety appliances for oil stills, having for an object to provide a thermo-controlled automatically operable valve for oil stills, whereby should the conduit leading from this still and employed to remove residue therefrom become broken at a point exteriorly of said still, the flow of residue being pumped into the conduit from the still will be immediately discontinued.

Other objects will be in part obvious and in part pointed out hereinafter.

It is well known in the oil refining industry that serious and extremely ruinous fires have been caused by the fracture of the residue conveying pipe at a point exteriorly of its still thus permitting the highly heated and volatile matter flowing therefrom to be supplied with that oxygen from the atmosphere necessary towards supporting spontaneous combustion with the resultant burning of the residue and the distilling apparatus. With the use of my improved arrangement, the danger of burning a material amount of the residue flowing from a fracture in the residue conveying pipe or the burning of the distilling apparatus resulting therefrom will be prevented.

In order that the invention and its mode of operation may be readily understood by persons skilled in the art, I have in the accompanying illustrative drawings and in the detailed following description based thereon, set out one possible embodiment of the same:

In these drawings:

Figure 1 is a vertical fragmental section through a portion of an oil still showing the improved valve applied thereto;

Figure 2 is a vertical section through the improved device showing the arrangement of the valve with relation to the outlet opening of the still through which the tar-like residue is pumped;

Figure 3 is a similar view wherein the

valve is shown in its open position together with the corresponding arrangement of the counterweighted actuating arm employed in connection therewith; and,

Figure 4 is a horizontal section taken on the line 4—4 of Figure 1 looking in the direction in which the arrows point.

Having more particular reference to the drawings in connection with which like characters of reference will designate corresponding parts throughout, the improved valve is to be used in connection with that type of oil still, the tank of which is fragmentally shown and designated by the numeral 1, such tank having an outlet port 2 in the rearward portion of the bottom thereof of receiving one end of a residue conveying pipe 3, by way of a nipple or similar joint 4; the mouth or inner end of said nipple 4 being beveled to provide a valve seat, the purpose of which will be hereinafter described.

Arranged within the still 1, is a substantially L-shaped supporting bracket 5 having one of the extremities thereof bent at substantially right angles as at 6 and welded or similarly connected to an adjacent portion of the still bottom, as shown in the Figure 1, while the opposite extremity of said bracket is likewise connected to an adjacent portion of the still. An L-arm 7 is connected to the vertical portion of the bracket 5 through the medium of bolts 8 and has an opening formed in its outer end adapted to movably receive the stem of the automatically operable valve there-through, whereby the engagement of such valve with its seat will be at all times ensured.

In order that the outlet opening in the still 1 may be closed upon the occurrence of an abnormal condition created by the breaking or fracturing of the residue conveying pipe 3, a plug valve 9 is provided and has a beveled engaging face 10 formed upon the free end thereof adapted to engage the beveled portion of the nipple 4 as shown in the Figures 1 and 2, a vertically disposed stem 11 extending from said valve through the openings in the L-arm 7 and through a similar opening formed in the upper or horizontal portion of the bracket 5. Because of the mounting of the stem 11 of the valve 9, it will be understood that the same will be, at all times, retained in vertical alignment with its seat and in consequence, movement of the

same thereonto, with the arise of any emergency, will be ensured.

In order that motion may be imparted to the valve 9 with the occurrence of an abnormal condition, an operating shaft 12 is mounted at one end in suitable bearings in the vertical portion of the bracket 5 as at 13, while the opposite end thereof extends through a combined journal box and packing 14 to a point exteriorly of the still 1. In this connection, it is to be noted that the inner end of the operating shaft 12 is mounted upon the vertical portion of the bracket 5 in a laterally off-set fashion, by reason 15 of the arrangement of the laterally extending arm 13 secured at one end to said vertical portion of the bracket 5 by means of bolts or similar fastening devices 15.

Spaced right angularly extending arms 20 16 are immovably secured to that portion of the operating shaft 12 directly in proximity to the vertical stem 11 of the valve 9 and have links 17 pivotally connected thereto as at 18, the free ends of said links 25 being similarly connected to the intermediate portion of the valve stem 11 as indicated at 19. Thus, it will be understood that with oscillatory movement of the operating shaft 12, reciprocal motion will be 30 imparted to the valve 9 by way of its stem 11, the arms 16 and the connecting links 17, hence, moving the same onto or from its seat as may be desired.

Fixedly mounted upon the squared outer 35 extremity 20 of the operating shaft 12 is an arm 21 carrying the weight 22 upon one end thereof, while the opposite end is apertured and receives a hook 23 in the same adapted to retain one end of a fusible link 40 24, the opposite end of which is engaged with a hook and eye arranged in the upper side of the counter weight 25.

Because of the counterweighted arrangement of the arm 21, it will be understood 45 that its normal position will be that as shown in the Figure 3, the weight 25 counterbalancing the weight 22 and normally retaining said arm in a substantially horizontal position, whereat the arrangement 50 of the arms 16 will be such as to retain the valve 9 in its uppermost position and spaced from the outlet 2 of the still 1, permitting the tar-like residue to be pumped from the still during its process of distillation.

55 The operation of the device may be reviewed as follows:

As above stated, under normal conditions, the valve 9 is retained in its uppermost position thus giving the tar-like residue free 60 access to the outlet opening 2 from whence it is directed into the conveying pipe 3. Should, however, the conveying pipe 3 become broken, a portion of the residue will immediately flow through the fractured 65 portion thereof and upon contacting with

the atmosphere, will be supplied with that amount of oxygen necessary towards creating spontaneous combustion. If the burning of the tar-like residue continues, the heat given off thereby will fuse the link 24, 70 which melts at 160-212° Fahrenheit, thus releasing the counterweight 25 from the apertured end of the arm 21 carrying the hook 23 and allowing it to drop under influence of the weight 22. With such movement of the arm, the operating shaft 12 will be rocked in a direction to impart a downward thrust to the coupling links 17 and since these links are connected to the arms 16 and to the intermediate portion of the 80 valve stem 11, the valve 9 thereupon will immediately move downwardly and over the valve seat formed in the upper portion of the nipple 4, thus positively closing the outlet 2 of the still and preventing any further pumping of residue into the pipe 3. The device, of course, may be readily reset by merely moving the now unweighted end of the arm 21 downwardly to a substantially horizontal position, as shown in dotted lines, in the Figure 3 and connecting the counterweight 25 to the hook 23 through the medium of a new fusible link or coupling 85 24.

Manifestly, the construction shown is capable of considerable modification and such modification as is within the scope of my claims, I consider within the spirit of my invention.

I claim:

1. In combination with a container having an outlet opening therein, a valve for closing said outlet opening, a shaft mounted in said container having one end connected to said valve for imparting reciprocal movement to the same, an arm fixedly mounted on the outer end of said shaft exteriorly of the container having one end weighted, a counterweight, and a fusible link for connecting the counterweight to the remaining end of said arm. 105

2. In combination with a container having an outlet opening therein, a valve for closing said outlet opening, a shaft mounted in said container, right angularly disposed arms fixedly mounted upon one portion of said shaft, connecting links pivotally connected to the free ends of said arms, a stem extending vertically from said valve and pivotally connected to the free ends of said links, an arm fixedly mounted on the other end of the shaft, having one end weighted, a counterweight, and a fusible link for connecting the counterweight to the remaining end of said arm. 115

3. In combination with a container having an outlet opening therein, a substantially L-shaped bracket arranged in and secured to portions of said container, a plug valve for closing said outlet opening, the

stem of said valve being disposed vertically and slidably engaged with portions of said L-shaped bracket, a shaft mounted at one end upon the vertical portion of said bracket and having its opposite end extended through one side wall of the container to a point exteriorly of the same, substantially right angularly disposed arms fixedly carried upon the inner portions of 10 said shaft, links pivoted to the outer ends

of said arms and at their remaining ends to the intermediate portion of the valve stem, an arm fixedly mounted upon the outer extremity of said shaft, a weight on one end of said arm, a counterweight, and 15 a fusible link for connecting said counterweight to the free end of the arm.

In witness whereof I have hereunto set my hand.

JAMES H. HESLAR.
